DESIGN FOR A SUIT

Jacob A. Silverman, New York, N. Y.

Application July 25, 1938, Serial No. 78,701

Term of patent 3½ years

To all whom it may concern:

Be it known that I, Jacob A. Silverman, a citizen of the United States of America, residing in New York city, in the Borough of Manhattan, County and State of New York, have invented a new, original, and ornamental Design for a Suit, of which the following is a specification, reference being had to the accompanying drawing, forming part thereof, wherein,

The design is characterized by the combination on the suit disclosed, of the specific superimposed stitched pockets arranged on the jacket as shown.

I claim:

The ornamental design for a suit, substantially as shown and described.

JACOB A. SILVERMAN.
